UNITED STATES PATENT OFFICE.

CHARLES H. HILDRETH AND CLIFTON C. DAUBENSPECK, OF OILFIELD, ILLINOIS.

ROTARY GAS-ENGINE.

1,113,993.

Specification of Letters Patent.

Patented Oct. 20, 1914.

Application filed January 3, 1914. Serial No. 810,201.

To all whom it may concern:

Be it known that we, CHARLES H. HILDRETH and CLIFTON C. DAUBENSPECK, citizens of the United States, residing at Oilfield, in the county of Clark and State of Illinois, have invented certain new and useful Improvements in Rotary Gas-Engines, of which the following is a specification, reference being had to the accompanying drawings.

This invention relates to new and useful improvements in internal combustion engines, and more particularly to rotary gas engines, and the primary object of the invention is to provide an engine wherein a maximum amount of power may be derived with the minimum fuel consumption.

A further object of the invention resides in the provision of an engine having a gas compressing attachment connected with the main cylinder or housing of the device and still another object of the invention resides in providing an improved hinged wall or valve connection between the compressing attachment and the main cylinder.

Still another object of the invention resides in providing a device which is simple and durable in construction, inexpensive to manufacture, and one which will be efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a vertical longitudinal section through a device 40 constructed in accordance with our invention. Fig. 2 is an opposite side elevation thereof, with parts broken away. Fig. 3 is a fragmentary transverse section as seen on line 3-3, Fig. 1. Fig. 4 is an elevation of the mechanical starting mechanism for the engine. Fig. 5 is a transverse section through the hinged wall arranged between the main housing or casing of the device and the gas compressing attachment. Fig. 6 is a plan view of the device shown in Fig. 5; and Fig. 7 is a detail section of the operating mechanism for the gas inlet valve of the device.

In describing our invention, we shall re-

fer to the drawings in which similar reference characters designate corresponding parts throughout the several views and in which—

1 indicates a cylinder or housing composed of an annular tubular member 2 constituting the main cylinder proper, and side covering plates 3, secured thereto. The cylinder 2 is formed in sections secured one to the other and extending through the axial centers of the side plates 3, is a central shaft 4, to which are secured in any preferred manner, radial arms 5, the outer ends of which are enlarged to provide heads 6. That portion of the cylinder 2 which may be considered the inner periphery thereof, is provided with a slot 7, and the heads 6 on the arms 5 are each provided with an extension stud or the like 8, which projects through the slot 7, and are threaded or otherwise secured to piston heads 9 mounted in the cylinder 2. These piston heads are circular in cross section and arcuate in longitudinal section to fit snugly in the cylinder 2 and, in order to prevent the gases which are adapted to be received in the cylinder 2, from escaping through the slot 7, an annular guard strip 10 is provided and secured to the outer faces of the head members 6. This guard fits snugly against the inner portion of the cylinder 2. The pistons 9 mounted upon the shaft 4 to rotate with the same form a rotor within the main cylinder.

Formed on or otherwise secured to the periphery of one section of the cylinder 2, is a tubular extension 11, constituting a plunger cylinder the outer end of which is covered by a removable plate 12 and this cylinder 11 communicates with the interior of the tubular member 2, through the medium of an opening formed in the latter.

Slidably mounted in the cylinder 11, is a plunger head 13 and a plunger head 14, said heads secured together and held in spaced relation, one to the other, through the medium of a connecting rod or arm 15. The plunger head 13 is disposed near the outer end of the cylinder 11, and inlet and outlet ports 16 and 17, respectively, are provided adjacent the outer end of the said cylinder, at diametrically opposite points thereon, said ports being covered by suitable check valves. Leading to the inlet port is

a conduit 18, extending from a carburetor (not shown), while an additional conduit 19 leads from the port 17 and extends to and in communication with a chamber 20 formed at the opposite end of the cylinder 11. This chamber is separated from the interior of the cylinder 11 by a wall 21 formed therein, and a spring held check valve 22 provided in the wall admits gases from the chamber to be passed to the inner end of the plunger cylinder at predetermined times.

Fulcrumed intermediate of its ends between the walls of the chamber 20 is an arm 23, one end of which is adapted to co-act with the free end of the stem of the valve 22. The wall 21 separating the chamber 20 from the interior of the plunger cylinder is provided with an opening 23', through which is slidably mounted a vertical stem 23^a, the upper end of which is adapted to contact with the opposite free end of the fulcrumed arm 23. The lower end of said stem 23^a has a roller 23^b carried thereon which, in the normal position of the stem, projects slightly through the opening 23' to a point within the cylinder 11. Thus, on the inward stroke of the plunger heads 13 and 14, the inner end of said plunger head 14 will contact with the roller 23^b, forcing the same upwardly and correspondingly oscillating the arm 23 on its fulcrum point. Such oscillation of the arm 23 will, obviously, cause the valve 22 to be opened thereby admitting gas, already under pressure, into the inner end of the cylinder 11.

In order to prevent the valve 22 from being retained in its open position for the full length of time that the plunger head 14 is in contact with the roller 23^b, the stem 23^a is formed of a pair of telescopic members 23^d and 23^e. A pin and slot connection is provided therebetween, as clearly shown in Fig. 7, and each of the telescopic members 23^d and 23^e is provided with a collar 23^f. A coil spring 23^g encircles this member 23^a between the collars 23^f, the tendency of said spring being to force said telescopic members in opposite directions to the normal position of the device, clearly shown in Fig. 7, whereby when the head 14 contacts with the roller 23 to force the latter upwardly, the complete stem 23^a will be forced upwardly to open the valve 22. When an explosion takes place, however, and the head 14 is still in contact with the roller 23, the force of the explosion will close said valve 22, which operation will cause the upper telescopic member 23^d to be moved in the lower telescopic member 23^e against the tension of the spring 23^g. As soon as the head 14 is forced to its extended position, however, the lower section 23^e of the stem 23^a will be forced to its initial position under tension of the spring 23^g. This structure

therefore permits the valve 22 to be properly actuated while the head 14 is in contact with the roller 23^b.

That portion of the cylinder 11, between the outer end wall 12 thereof and the piston head 13, forms a compressor, it being understood that the gas is received therein from the pipe or conduit 18 and passes, under compression, through the pipe or conduit 19 to the gas chamber 20 from where it is admitted, at predetermined times, to the firing or combustion chamber 24. This chamber is formed at the extreme inner end of the cylinder 11, at a point immediately below the wall 21 formed between said cylinder 11 and the chamber 20 and a spark plug 25 of any preferred character is operatively mounted in the wall of the chamber 24.

As stated, the cylinder 11 communicates with the interior of the cylinder 2 and, in order to permit the force of the explosion of the chamber 24 to be directed in but one way, through the cylinder 2, a valve 26 is provided which is hinged, at the point of intersection between one wall of the cylinder 11 and the cylinder 2. This valve 26 is of such design as to form both a part of the cylinder 11 and a part of the cylinder 2, the exact formation of which is clearly disclosed in Fig. 5 of the drawings. This valve 26 is adapted, through gravity, to be disposed across the path of the pistons 9 in the member 2 and in order to prevent the pistons from striking this valve as the former are rotated in the cylinder 2, I provide a means for retaining the valve 26 normally in a raised position. To this end, an extension arm 26' is formed at the hinged end of the valve 26 and projects through a slot or opening in the adjacent portion of the cylinder 2. A coil spring 26^a is engaged with the free end of arm 26' and is adjustably secured, as shown at 26^b to the outer face of the wall of the cylinder 2. The valve 26 will, therefore, be yieldingly retained in its raised position, and thus completes the formation of the cylinder 2 for the clear rotation of the pistons 9 therein. A projection 34, however, is provided on the inner end of the plunger-head 14 which, upon the instroke of the latter is adapted to contact with the inner hinged end of the valve 26 to force the latter to its closed position, as shown in Fig. 1. The explosion takes place in the chamber 24, when the valve 26 is in its lowered position, and the force of the explosion will be directed against the plunger head 14, and one wall of an adjacent piston 9, as well as against the valve 26, which forms a base or flooring for the chamber 24. The force of the explosion will, of course, direct the plunger 14 outwardly in the cylinder 11 and will force the pistons 9 around the cylinder 2 in the direction of the arrow shown in Fig. 1. As soon as the plunger 14

head 14 is directed outwardly, the valve 26 will be raised under tension of the spring 26^a. The gases and products of combustion which are in the cylinder 2 will be carried 5 partially around the same and exhausted through the pipe 27 which is suitably mounted at a desired point on the cylinder and it will be understood that as the one piston head is forced in the direction of the arrow 10 in Fig. 1, the other piston heads in connection therewith and in fact the complete rotor will be revolved in the main casing or housing 1.

We have provided for the actuation of the 15 piston and plunger heads 13 and 14 simultaneously with the rotation of the rotor and, to this end, an enlarged gear 29 is mounted on the shaft 4, just beyond the casing or housing 1. Arranged in connection with the 20 gear 29, is a pinion 30 which has an eccentric 31 operatively connected thereto and a longitudinal rod or shaft 32 operatively connects at its one end with this eccentric 31. The 25 opposite end of this rod or arm 32 has a transversely extending connection 33 suitably engaged therewith, which projects through a slot 34 in the side of the extension 11. This projection 33 connects with the arm 15 and, from this description, it will be 30 seen that the heads 13 and 14 will be reciprocated in the cylinder 11, as the rotor revolves in the main cylinder 1. We have also provided a means for starting this engine and, in carrying out this idea, a ratchet 35 35 is mounted on the shaft 4. Loosely mounted on this shaft 4, is an arm 36 which carries a pawl 37, the latter being normally held in engagement with the teeth of the ratchet by means of a coil spring 38. The outer end of 40 the arm 36 has a link 39 pivotally engaged therewith, the opposite end of said link being pivoted intermediate of the ends of an arm 40. This latter arm is fulcrumed at its one end to an object and the opposite end 45 has pivoted connection with an additional link 41. This link is in turn, pivotally connected intermediate of the ends of an actuating lever 42 which is fulcrumed at one end to a fixed support. It will be seen, from 50 this construction, that as the lever is swung in the direction of the arrow shown in Fig. 4, the ratchet 35 will be turned in a reverse direction, thereby rotating the shaft 4 and starting the device.

55 In operation, the lever 42 is first actuated on its fulcrum point to set the shaft 4 in rotation and start the device. As the rotor revolves, the piston and plunger heads 13 and 14, respectively, will be reciprocated in 55 the cylinder 11. Upon the instroke of the piston head 13, the valve 16 will be opened to admit gas from the carburetor to the outer end of the cylinder 11 which, as heretofore stated, forms a compressor. Upon the 65 outward stroke of the piston head, the gas

will be compressed against the outer wall of the cylinder and forcing the valve 17 to its open position, will be directed through the conduit 19 to the gas chamber 20. It will be understood from the foregoing description of the device that as the rotor revolves, the plunger heads 13 and 14 will be reciprocated in the cylinder 11 and it is also understood that the valve 26 is adapted to be normally disposed to its raised position, 70 as shown in Fig. 1, and forced to its lowered position upon the instroke of the plunger head 14. The return of the valve 26 to its lowered or closed position, completes the formation of the lower portion of the cylinder 11, so that the plunger head 14 may continue on its instroke and, as it continues on its instroke, the head will contact with the roller 23^b to cause the valve 22 to be opened. As the valve 22 is opened, gas 80 which has already been compressed, will enter the explosion chamber 24. The explosion will, obviously, force the adjacent piston head 9 of the rotor in the direction of the arrow, causing the rotor to be continued 85 in its revolution and the plunger heads to be directed outwardly in the cylinder 11. It is to be understood that the pinion 30 makes three revolutions during each revolution of the gear 29. The parts are so proportioned and their operations so timed as to cause the plunger head 14 to force the valve 26 to its open position immediately 90 after each piston 9 passes through the explosion chamber 24, the valve 22 being simultaneously opened as above explained to admit the charge to said chamber. This charge, of course, is compressed between the end of the plunger 14 and the end of the piston 9, the spark being created through 95 the medium of a suitable timing device to explode the same. Before the next succeeding piston 9 moves into the explosion chamber 24, the plunger 14 will have been forced outwardly in the plunger cylinder and the 100 valve 26 returned to its normal position by the spring 26^a, so that said valve will not interfere with the movement of the pistons.

110 From the foregoing it will be seen that we have provided a simple, inexpensive and efficient means for carrying out the objects of the invention and while we have particularly described the elements best adapted to perform the functions set forth, it is obvious that various changes in form, proportion and in the minor details of construction may be resorted to without departing from the spirit or sacrificing any of the principles of the invention.

115 Having thus described this invention, what we claim is:

1. An engine of the class described including a casing provided with a passage-way, a rotor operatively mounted therein, a tubular extension formed on said casing 120

125

substantially tangential thereto and communicating therewith, a hinged member mounted at the junction of the extension and said casing adapted to normally form an obstruction in the passage-way of the casing, said hinged member being designed to conform respectively to the outline of the casing and the extension to complete the formation thereof, one at a time, at the junction of said extension and casing, means for supplying an explosive mixture to said extension, means within said extension for compressing the mixture therein, and additional means for passing the compressed mixture to the inner end of said extension at predetermined times.

2. An engine of the class described including a casing provided with a passage-way, a rotor operatively mounted therein, an extension formed on the casing substantially tangential to the periphery of the latter and communicating with the interior thereof, the inner end of said extension at the point of communication thereof with the casing being designed to form an explosion chamber, an oscillating valve member mounted at the junction of the extension and casing and adapted to form an obstruction in the passage-way of the latter and also designed to form a wall of said explosion chamber, said valve member being also designed to conform respectively to the contour of the extension and casing at the junction thereof when said valve member is respectively disposed to the extremities of its movement, means to supply an explosive mixture to said extension, means for compressing the mixture in said extension, and means coöperating with the last referred to

means for admitting the compressed mixture to the explosion chamber at predetermined times.

3. An engine of the class described comprising a tubular member of annular design formed in sections secured one to the other to form a casing having a passage-way, pistons operatively mounted therein, a tubular extension formed on one of the sections of said annular member, substantially tangential thereto and communicating with the interior thereof, a valve member hinged at the point of junction between the extension and the one section of the casing, said valve member being designed on its one face to conform to the contour of the tubular casing when said valve is disposed in one position and having its opposite face designed to conform to the contour of the tubular extension when said valve is disposed in an opposite position, said valve member in the last mentioned position forming an obstruction in the passage-way of the casing, means for supplying an explosive mixture to the outer end of said extension, means for compressing said mixture in the extension, and means for admitting the compressed mixture at predetermined times to the inner end of the extension at the junction thereof with the casing.

In testimony whereof we hereunto affix our signatures in the presence of two witnesses.

CHARLES H. HILDRETH.
